UNITED STATES PATENT OFFICE.

HERBERT S. HUMPHREY, OF KALAMAZOO, MICHIGAN:

WATER-HEATER.

998,004.

Specification of Letters Patent. Patented July 18, 1911.

Application filed February 24, 1908. Serial No. 417,344.

To all whom it may concern:

Be it known that I, HERBERT S. HUMPHREY, a citizen of the United States, residing in the city and county of Kalamazoo, 5 State of Michigan, have invented certain new and useful Improvements in Water-Heaters, of which the following is a specification.

This invention relates to improvements in 10 water heaters.

The main objects of this invention are: First, to provide an improved water heater which is adapted to quickly and automatically supply hot water, which may be operated at a comparatively small cost. Second, to provide an improved water heater in which the water circulates freely through the heater when the water is not being drawn off therefrom, thereby maintaining 20 the water at an even temperature and reducing the consumption of fuel to the amount necessary to maintain that temperature. Third, to provide an improved structure of the class described, in which 25 the gas burners are controlled by a thermostat.

Further objects, and objects relating to structural details, will definitely appear from the detailed description to follow.

30 I accomplish the objects of my invention by the devices and means described in the following specification.

The invention is clearly defined and pointed out in the claims.

35 A structure embodying the features of my invention is clearly illustrated in the accompanying drawing, forming a part of this specification, in which.

Figure 1 is a detail side elevation of a 40 structure embodying the features of my invention, portions being broken away to show the arrangement of the parts. Fig. 2 is an enlarged detail vertical section, taken on a line corresponding to line 2-2 of Fig. 1, 45 portions being broken away to show the arrangement of the parts. Fig. 3 is an enlarged detail section, taken on a line corresponding to line 3-3 of Fig. 2, showing details of the circulation valve, the valve 50 itself being shown in full lines. Fig. 4 is an enlarged detail taken on a line corresponding to line 4-4 of Fig. 2, the valve 20 being shown in full lines, and in its closed position. Fig. 5 is a detail vertical section 55 through the circulation valve showing structural details thereof. Fig. 6 is an en-

larged detail vertical section taken on a line corresponding to line 6-6 of Fig. 3.

In the drawing, the sectional views are taken looking in the direction of the little arrows at the ends of the section lines, and similar numerals of reference refer to similar parts throughout the several views.

Referring to the drawing, 1 represents the casing of my improved water heater; 2 the heating coils; and 3 the burners. The water inlet 4 for the heater is preferably controlled by the automatic valve 5, which controls the delivery from the water supply 6. The water inlet valve is preferably the type of water valve shown in Letters Patent No. 791028, issued to me on May 30th, 1905, being an automatic water and gas valve. The gas supply pipe 7 is controlled by a gas valve 8, which is preferably the type of gas valve shown in my application for Letters Patent for water heaters filed September 12, 1907, Serial No. 392,595, the water valve being connected to open the gas valve by the rod or stem 9, so that the gas valve is automatically opened by the water valve.

The water valve piston 22 is actuated by the water, as stated, and it in turn actuates the gas valve 23 through the valve stems 9. The spring 24 returns the piston 22 to its initial position, and the spring 25 returns the gas valve. The auxiliary gas valve 26 is held normally in the seat by the spring 27, and is held open when the temperature of the water is below a predetermined point by the thermostat 11, one member 28 of which acts on the valve through the levers 29 and 30 (see Fig. 2). These parts are not described in further detail herein as they form no part of my present invention.

I illustrate at 12 in a conventional form a draw-off faucet for the heater discharge pipe. When the faucet is opened, or water is being drawn off, the pressure in the water supply pipe 6 opens the water inlet valve 5, and through its connection with the gas valve admits the gas to the burners, a suitable pilot as 13 being provided so that the burners are automatically ignited. The incoming water passes through the water inlet 4 of the heater down through the heater and out through the heater discharge 10 and the thermostat tube 21 located therein to the faucet. When the water, being drawn off, reaches a predetermined temperature, the gas valve is automatically closed or partially

closed by means of the thermostat. When the faucet or draw-off cock 12 is closed, the pressure equalizes and the valve 5 is automatically closed. In order to permit the circulation of water through the heater, when no water is being drawn off therefrom, I provide a circulation or return pipe 14, which connects the discharge of the heater to the inlet, so that the water circulates through the discharge pipe and thermostat tube 21 to the return or circulation pipe 14, thence to the inlet 4, and through the heater, thus circulating past the thermostat, which controls the gas valve and maintains the water in the heater at a predetermined or approximately at a predetermined temperature.

In order to control the inlet and the return or circulation pipe, I provide a circulation valve 20 preferably consisting of the valve member 15, which is adapted, when closed, to seat upwardly against the seat 16, thereby closing the circulation or return pipe. The valve member 15 is provided with a downwardly-projecting stem 17, on which the inlet valve member 18 is slidably mounted.

Between the valve members 15 and 18 I arrange a spring 19. The valve members 15 and 18 are so arranged that the valve member 15 closes before the valve member 18 opens, and vice versa; the spring 19 being compressed when the valve member 18 is opened by the incoming water. By this arrangement I secure in a simple and effective manner an automatic valve which effectively controls the circulation. I show one form of this circulation feature in my co-pending case hereinbefore referred to, in which the circulation valve is controlled directly by the water inlet valve, and I present claims broadly to the circulation feature in that application. This form of my invention, however, has certain advantages in regard to the arrangement and location of the parts, and is the embodiment of my invention preferred by me where a storage tank or extensive circulating system, such as I have indicated in conventional form in my said co-pending application before referred to, is not desired.

The valve 20, shown in detail in Fig. 4, is adapted to control the discharge of the heater,—that is, it may be adjusted to control the quantity of water drawn off during any given time, it being intended that this shall be shut off according to the capacity of the heater.

I have illustrated and described my invention in detail in the form preferred by me on account of structural simplicity and economy. I am, however, aware that it is capable of considerable variation in structural details without departing from my invention.

Having thus described my invention, what

I claim as new and desire to secure by Letters Patent, is:

1. The combination with a water heater, of a gas burner therefor; a gas valve arranged to control said burner; a water inlet for said heater; an automatic water inlet valve arranged to open said gas valve; a water discharge for said heater; a thermostat connected to said gas valve; a return or circulation connection for said water discharge and water inlets; an automatic circulation valve comprising a circulation valve member, said circulation valve member having a downwardly-projecting stem, an inlet valve member slidably mounted on the stem of said circulation valve member, and a spring interposed between said valve members, said circulation valve member being adapted to close before said inlet valve member is opened and vice versa. 85

2. The combination with a water heater, of a gas burner therefor; a gas valve arranged to control said burner; a water inlet for said heater; an automatic water inlet valve arranged to open said gas valve; a water discharge for said heater; a thermostat connected to said valve; a return or circulation connection for said water discharge and water inlets; an automatic circulation valve comprising a circulation valve member, an inlet valve member, and a spring interposed between said valve members, said circulation valve member being adapted to close before said inlet valve member is opened and vice versa. 90

3. The combination with a water heater, of a gas burner therefor; a gas valve arranged to control said burner; a water inlet for said heater; an automatic water inlet valve arranged to open said gas valve; a water discharge for said heater; a thermostat connected to said gas valve; a return or circulation connection for said water discharge and water inlets; an automatic circulation valve comprising a circulation valve member, said circulation valve member having a downwardly-projecting stem, and an inlet valve member slidably mounted on the stem of said circulation valve member, said circulation valve member being adapted to close before said inlet valve member is opened and vice versa. 10

4. The combination with a water heater, of a gas burner therefor; a gas valve arranged to control said burner; a water inlet for said heater; an automatic water inlet valve arranged to open said gas valve; a water discharge for said heater; a return or circulation connection for said water discharge and water inlets; an automatic circulation valve comprising a circulation valve member, said circulation valve member having a stem, an inlet valve member slidably mounted on the stem of said circulation valve member, and a spring inter- 1

posed between said valve members, said circulation valve member being adapted to close before said inlet valve member is opened and vice versa.

- 5 5. The combination with a water heater, of a gas burner therefor; a gas valve arranged to control said burner; a water inlet for said heater; an automatic water inlet valve arranged to open said gas valve; 10 a water discharge for said heater; a return or circulation connection for said water discharge and water inlets; an automatic circulation valve comprising a circulation valve member, said circulation valve member having a stem, and an inlet valve member slidably mounted on the stem of said circulation valve member, said circulation valve member being adapted to close before said inlet valve member is opened and vice versa.
- 15 15. Interposed between said valve members, said circulation valve member being adapted to close before said inlet valve member is opened and vice versa.
6. The combination with a water heater, 20 of a gas burner therefor; a gas valve ar-

ranged to control said burner; a water inlet for said heater; an automatic water inlet valve arranged to open said gas valve; a water discharge for said heater; a return or circulation connection for said water discharge and water inlets; an automatic circulation valve comprising a circulation valve member, said circulation valve member having a stem, and an inlet valve member slidably mounted on the stem of said circulation valve member, said circulation valve member being adapted to close before said inlet valve member is opened and vice versa.

In witness whereof, I have hereunto set my hand and seal in the presence of two 35 witnesses.
